UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

METHOD OF MAKING SOCKET-WRENCH HEADS.

Application filed June 5, 1919, Serial No. 301,865. Renewed February 20, 1922. Serial No. 538,097.

To all whom it may concern:

Be it known that I, HJALMAR G. CARLSON, a citizen of the United States, residing at Worcester, in the county of Worcester and 5 State of Massachusetts, have invented a new and useful Method of Making Socket-Wrench Heads, of which the following is a specification.

This invention relates to a method of 10 working sheet metal, capable of general use, but particularly adapted for the manufacture of socket wrench heads. These heads have been made heretofore usually from solid metal by comparatively expensive 15 processes; and this invention is designed to greatly reduce the expense of manufacture.

The invention involves the forming of a 20 flat blank of sheet metal unto a cup shape. The closed end is reduced without reducing 25 the cylindrical open end. This blank is drawn between the punch and die by a longitudinal, that is axial pressure, to further reduce the closed end and flatten it so that the flattening operation will be done by the 30 drawing process and the metal will flow inwardly toward the plunger which is shaped to provide a passage of the desired non-circular form through the blank. Then the 35 blank is punched clear through the closed end to continue the non-circular shape and provide an opening for the wrench handle, and finally the finished external and internal shape is given to the open end, as for 40 example, it is made into a hexagon if it is to be used for a hex nut. Although this represents briefly the preferred way of carrying out the process, it is to be understood that I do not limit myself to all the steps or details thereof except as expressed in the 45 claims.

Reference is to be had to the accompanying drawings, in which

Figs. 1, 2 and 3 are central sectional views 45 of a blank showing three of the early steps in the process of manufacture;

Fig. 4 is a sectional view of a die with the blank therein and the plunger brought into position to permit the next drawing operation;

Fig. 5 is a side view of the blank in the 50 same condition with parts shown in section;

Fig. 6 is an end view of the open end of the blank;

Fig. 7 is an end view of the closed end; 55

Fig. 8 is a sectional view of the next die into which the blank is placed showing the punching through the end of the blank;

Fig. 9 is an end view of the blank in the same condition as shown in Fig. 8; 60

Fig. 10 is a side view partly in section of the finished article;

Fig. 11 is an end view of the same, and

Fig. 12 is a side view of the finished head and handle. 65

I have not shown the original flat blank of which the article is to be made, but in Fig. 1 have shown it at A after it has been subjected to the first drawing operation. The second operation produces the blank B 70 shown in Fig. 2 by elongating the blank shown in Fig. 1 and reducing its diameter. It is of a general cylindrical form with one open end and the other end closed by a convex end wall. The steps required to produce the 75 first two blanks are common in this industry and need not be described in detail, and it is to be understood furthermore that whether it takes one, two, or more operations to get the blank ready for the next step depends 80 upon the character and thickness of the metal employed.

In Fig. 3 I have shown the blank C as having passed through another drawing operation in a die of circular cross section, being punched into it by means of a plunger 85 also having a circular cross section, the die and plunger being smaller at one end than at the other end and the blank being ejected after it is formed in the usual way. It will 90 not be necessary to describe the details of the die and plunger, but they produce from the blank B shown in Fig. 2 the blank C shown in Fig. 3. The open end of this blank at 12 is shown as substantially cylindrical 95 and of the same diameter as the cylindrical portion of the blank B. This cylindrical portion extends only a short distance from the open end and the blank is then contracted to form a cylindrical portion 13 of 100 smaller diameter which is closed by a bottom 14. The thickness of the metal throughout this blank is almost uniform, although there is a slight thinning just above the circumference of the bottom 14 at the point 15, 105 due to the elongation of the metal in this manner.

This blank C is then placed in a die 16

and operated on by a punch or plunger 17 to produce the modified blank D. The die 16 has a circular portion at the top of the same diameter as the part 12, which produces an elongated cylinder 22 at the open end of the blank, the plunger 17 being cylindrical at this point and having a sharp shoulder at 18. The plunger also has a reduced portion 19 which is flattened on two sides. 10 The die 16 also has a shaping cavity at the bottom which is of a general cylindrical shape throughout a part of its periphery, but is provided with two flat portions on opposite sides corresponding in position to the flattened parts of the plunger 19. This produces a wall 23 on the article which is provided with two flat surfaces 26 and two other surfaces 27 which constitute part of the same cylinder. The thickness of the metal all 20 around this portion is substantially the same because the shape of the plunger extension 19 that I have described above provides two opposite flat walls 29 parallel with the walls 26. 25 The blank D, having been formed as above described and ejected, is placed in another die 36 which is not designed to change materially the outside shape of the article, but differs from the die 16 mainly in that it is 30 open at the bottom. Then the plunger 37 having a shape and size substantially the same as that of the plunger extension 19 is forced down through the blank to punch out a hole 34 in the bottom of it of the same 35 shape and size as the passage in the blank D. This produces the blank E.

The next step of the process consists, in this form of the invention, in shaping this blank E in suitable dies, not shown, to produce the blank F which differs from the blank E merely in having its external surface lengthened and changed from the cylindrical shape to a hexagonal shape at 32. Inside it is also given a hexagonal shape at 33. 40 Of course if any other shape is desired that will be within the scope of this invention.

It is to be understood that this opening 34 is provided for the reception of the flat end of a wrench handle 38 which is inserted in 50 the opening and headed over inside so as to form a complete socket wrench as shown in Fig. 11 if that is the object aimed at. Or it can be left detachable as shown for fitting a plurality of socket heads. It is to be observed that the extension 19 and plunger 37 55 are non-circular so that the end of the handle 38 can be made of similar shape in a very simple manner out of round bar iron.

In describing the preferred way of carrying out the invention I have specified merely the mechanical steps without calling attention to the details and specific results thereof. It is to be noted, however, that the formation of the blank D from the blank C 60 is accomplished by flattening the cylindrical

closed end of the blank by a longitudinal or axial drawing process. This naturally forces the metal upwardly along the two opposite inclined or curved surfaces 20 of the die 16 and furnishes the metal to form the square 70 shoulder 18 on the inside of the blank D. This is a drawing or displacement process and moves the metal longitudinally in a manner that could not be accomplished by a mere compression of the blank to flatten it 75 on opposite sides. Such a pressure would tend to increase the diameter of the curved surfaces instead of forcing the metal back into the shoulder as stated above.

In this way an article of the class described, or of any generally similar form, can be produced by a series of the simplest kind of metal drawing operations from sheet metal, and thus when it is to be produced in large quantities a very material saving can 80 be effected in the manufacture. At the same time a product is secured which is uniform, strong, and light and is not likely to have any cracks or imperfections if made from ordinary qualities of sheet metal that are 90 on the market.

Although I have illustrated and described only a single form of the invention and shown it as applied to the manufacture only of a single article I am aware of the fact 95 that changes in the procedure can be made and that the invention can be used broadly in this art for the manufacture of other articles without departing from the scope of the invention as expressed in the claims.

Therefore I do not wish to be limited in these respects, but what I do claim is: —

1. The method of making a hollow article which comprises shaping a piece of sheet metal into the form of a hollow member having an open end and a closed end, flattening the closed end on opposite sides, then punching a non-circular hole through the closed end wall, and finally shaping the open end. 100

2. The method of making a socket wrench which consists in shaping a piece of metal into the form of a hollow member having a closed end and an open end, drawing it out to reduce its diameter at the closed end 105 and flattening it on opposite sides, then punching a hole through the closed end wall, and finally shaping the open end. 115

3. The method of making a socket wrench head which comprises shaping a piece of sheet metal by die punching operations into the form of a member having a rounded closed end, reducing and simultaneously flattening the opposite sides of the closed end, by a drawing operation without modifying the open end, then punching a non-circular hole through the closed end wall for the reception of the end of a handle. 120

4. The method of making a socket wrench head which consists in shaping a piece of 130

sheet metal into the form of an open ended cylinder having a closed end, reducing and simultaneously flattening the closed end, without modifying the shape of the open end, by a longitudinal drawing operation, 5 then punching a non-circular hole through the closed end for the reception of the end of a handle.

5. The method of making a socket wrench 10 head which consists in shaping a piece of sheet metal by die punching operations into the form of an open ended cylinder having a rounded closed end, reducing and simultaneously flattening the closed end and 15 the central passage therein, without modifying the open end, by a drawing operation, leaving the narrow dimension of the passage slightly less than the diameter of the reduced passage at its mouth, then punching 20 a non-circular hole through the closed end of the same size and shape as the flattened passage for the reception of the end of a handle, and finally giving the open end the desired shape to fit a nut.

25. 6. The method of making an article of the class described, which comprises shaping a blank from sheet metal to give it an open end and a reduced closed end flattened on opposite sides and convex on its intermediate surfaces, and punching out the center of the closed end to produce a non-circular perforation having opposite flat sides 30 parallel with the flat sides of the exterior.

7. The method of making an article of 35 the class described, which comprises pro-

ducing a blank from sheet metal having an open end and a reduced closed end flattened on opposite sides, and punching out a non-circular perforation in the center of the closed end.

8. The method of making a socket wrench 40 which consists in shaping a piece of sheet metal into the form of an open ended cylinder having a closed end, reducing and flattening the closed end, then punching a 45 non-circular hole through the closed end, giving the open end the desired shape to fit a nut, inserting a piece of bar iron flattened on the end into said hole, and heading it over inside.

9. The method of making a socket wrench 50 which consists in shaping a piece of sheet metal by die punching operations into the form of an open ended cylinder having a rounded closed end, reducing and flattening 55 the closed end and the central passage therein, by a drawing operation, leaving the narrow dimension of the passage slightly less than the diameter of the reduced passage at its mouth, then punching a non- 60 circular hole through the closed end of the same size and shape as the flattened passage, giving the open end the desired shape, inserting a piece of bar iron flattened on 65 the end into said hole, and heading it over inside.

In testimony whereof I have hereunto affixed my signature.

HJALMAR G. CARLSON.
